US0D1022149S

(12) **United States Design Patent** (10) Patent No.: **US D1,022,149 S**
(45) Date of Patent: ** Apr. 9, 2024

(54) **FLUIDIC COUPLING**

(71) Applicant: **Caroma Industries Limited**, North Sydney (AU)

(72) Inventor: **Stephen McCutcheon**, Auckland (NZ)

(73) Assignee: **Caroma Industries Limited**, North Sydney (AU)

(**) Term: **15 Years**

(21) Appl. No.: **29/817,244**

(22) Filed: **Nov. 30, 2021**

(30) **Foreign Application Priority Data**

May 31, 2021 (AU) 202113135

(51) **LOC (14) Cl.** **23-01**

(52) **U.S. Cl.**

USPC **D23/262**; D23/304; D23/263

(57) **CLAIM**

The ornamental design for a fluidic coupling, as shown and described.

DESCRIPTION

FIG. 1 is a perspective view of a top, front, and right side of a fluidic coupling;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The evenly spaced broken lines depict portions of the fluidic coupling that form no part of the claim.

1 Claim, 7 Drawing Sheets
